UNITED STATES PATENT OFFICE

160,996

ATOMIZER

George Carleton, New York, N. Y.

Application April 20, 1949, Serial No. 2,165

Term of patent 7 years

(Cl. D83—1)

To all whom it may concern:

Be it known that I, George Carleton, a citizen of the United States, residing in New York, in the county of New York and State of New York, have invented a new, original, and ornamental Design for an Atomizer, of which the following is a specification, reference being had to the accompanying drawing, forming a part thereof.

Fig. 1 is a top plan view of an atomizer, showing my new design;

Fig. 2 is a front view of the atomizer;

Fig. 3 is a view of one side of the atomizer, and

Fig. 4 is a view of the other side of the atomizer.

The dominant features of my design reside in the portions shown in full lines.

I claim:

The ornamental design for an atomizer, as shown and described.

GEORGE CARLETON.
